CLAIM

We claim the ornamental design for a keyboard, as shown and described.

DESCRIPTION

FIG. 1 is a front, top, and right side perspective view of a keyboard with a display in a flush position;

FIG. 2 is a top plan view thereof;

FIG. 3 is a front side elevational view thereof with keyboard supports in an extended position;

FIG. 4 is a back side elevational view thereof;

FIG. 5 is a bottom plan view thereof;

FIG. 6 is a right side elevational view thereof;

FIG. 7 is a left side elevational view thereof;

FIG. 8 is a front, top, and right-side perspective view thereof with the display in an upright position; and,

FIG. 9 is a front side elevational view thereof with keyboard supports in a retracted position.
